UNITED STATES PATENT OFFICE.

HERMANN J. SCHUBERT, OF HACKENSACK, NEW JERSEY.

CONSTRUCTION OF BUILDING-WALLS.

1,056,948.

Specification of Letters Patent. Patented Mar. 25, 1913.

Application filed April 27, 1909. Serial No. 492,493.

To all whom it may concern:

Be it known that I, HERMANN J. SCHUBERT, a citizen of the United States, residing at Hackensack, in the county of Bergen and 5 State of New Jersey, have invented a certain new and useful Improvement in the Construction of Building-Walls, of which the following is a specification.

I will first describe the improvement in 10 detail and then point out the novel features in the claims.

In the accompanying drawings Figure 1 is a general side view of the apparatus which I use in the construction of building 15 walls, showing a partial view of the wall as completed; Fig. 2 is a plan view of the apparatus shown in Fig. 1, and of part of the wall as completed; Fig. 3 is a partial enlarged view of the apparatus illustrated in 20 Fig. 2 showing cores in position before the material is poured in; Fig. 4 is an enlarged sectional view taken on the plane of the dotted lines 4—4, Fig. 2; Fig. 5 is a sectional view taken on the plane of the dotted lines 5—5 25 Fig. 4; Fig. 6 is a perspective view of a core; Fig. 7 is a plan view showing a core contracted; Fig. 8 is a plan view showing a core expanded; Fig. 9 is a partial enlarged view taken on the plane of the dotted lines 30 9—9, Fig. 6, the core being contracted; Fig. 10 is a view of a core taken approximately on the lines 9—9 Fig. 6, the core being expanded; Figs. 11 and 12 are partial enlarged 35 views of the inside of a core showing an arrangement by which the core is contracted and expanded; Fig. 13 is an enlarged sectional view taken on the plane of the dotted lines 4—4 Fig. 2, the apparatus employed in the construction of walls being shown as 40 supported on a completed section of wall; Fig. 14 is a partial side view of the apparatus employed in the construction of walls when supported on a completed section of wall; Fig. 15 is a detail view of parts of the 45 apparatus which I employ in the construction of walls.

Similar letters of reference designate corresponding parts in all the figures.

A, A¹, designate uprights shown as fastened to a cross-piece, A². These uprights, A, A¹, are preferably made of wood which has a certain amount of resiliency. In order to give additional strength to the uprights, A, A¹, they may be provided with facings, 50 as a¹, of metal fastened to the uprights by

screws, as a³. Braces A³, may be employed to aid in holding the uprights, A, A¹, and the cross-piece, A², together. The cross-piece, A², may likewise be provided with a facing, as a², of metal, to impart additional 60 strength.

B designates a rod shown as screw threaded and provided with a nut, b, at one of its ends. If desired, this rod, B, may be screw threaded and provided with nuts at both its 65 ends.

A cross bar, C, is shown as fastened to the uprights, A and A¹, and this cross bar, C, is shown as provided with a series of holes, c.

A bar, D, is shown as suspended from the 70 cross bar C. In this bar, D, racks, as F, are shown as fastened, and the teeth of the racks, F, are designed to fit into the projections, g, of pieces, G, fastened to the upright, A.

I have shown a bar, H, fastened at its 75 upper end to the cross bar, C, and as provided at its lower end with a slot, h. A headed bolt, A⁴, on the frame A¹, may be inserted in this slot h, and thereby the bar, H, will be held securely in place. Instead, 80 however, of using the slot, h, I may hold the lower end of the bar, H, in place in any desired manner.

I, I¹, designate the sides of a mold. These sides, I, I¹, are shown as made of pieces, i, 85 of board having frames, as i¹, shown as extending beyond the outer surfaces of the sides, I, I¹, and the upper surfaces of these frames, i¹, may be provided with holes, i². The frames i¹, may fit into pieces, j, shown 90 as fastened to the bars D and H. Cross pieces, i³, may be employed to hold the pieces i together, and instead of holding the sides, I, I¹, and the bars D and H together in the manner illustrated, the sides I, I¹, 95 may be secured to the bars, D and H, in any desired manner.

The inner surfaces of the sides, I, I¹, may be covered with any appropriate material, such, for instance, as zinc, and if it be desired that the finished wall should be ornamented the inner surfaces of the sides, I, I¹, may be so designed as to give the desired ornamentation to the wall. 100

J designates a piece, one end of which is 105 shown as passing through the side, I¹, and the other end of which is shown as fitting in a groove in the outer surface of the side, I¹. The outer end of the piece, J, is shown as slotted at j². A lock, j³, is shown as 110

- provided on the outer surface of the side I^1 , through which the piece J , is inserted, and by turning this lock, J^2 , the piece, J , may be unlocked and withdrawn. These pieces, J , may, if desired, be used on both the sides, I and I^1 , or their use may be entirely dispensed with, but I prefer to use them on that side which is to be the inside of the completed wall.
- 10 My preferred construction of core, as illustrated, is bi-lateral in form having its two side-portions integrally united by a reduced neck portion, whose outer surface is continuous with that of the side-portions, and likewise the outer surface of the oppositely disposed lateral extensions from the body-portions is within the plane of the corresponding surfaces of the side-portions, the two planes mentioned having been shown 15 parallel and co-incident with the respective inner surfaces of the two walls to be constructed by my apparatus.
- While the bi-lateral form of core with a right and a left hand member substantially 20 as shown, may be generally employed as a matter of convenience in practising my invention, yet in constructing walls of certain given dimensions it will often be required to use a right hand, or a left hand, 25 core unit-section singly. Consequently I do not desire to be limited to the use of the one form or the other, or to have the double form of construction considered as embodying the fundamental or basic principles 30 of my invention, notwithstanding that in the description following, I minutely describe the aforesaid bi-lateral construction of core.
- My preferred form likewise shows the 35 core composed practically of an outer and an inner wall or side with means, shown in detail, for expanding said side walls which have been referred to as collapsible means and which operations may assist in the 40 operation of removing the core. I do not wish, however, to be limited to these features as my only means for withdrawing the core after casting, for it is obvious that with lifting power suitably applied to the 45 top portions the same may be withdrawn without first "collapsing" the shell walls as shown. I therefore desire broad protection in this feature also which is a necessary provision in the operation of my apparatus.
- 50 The cores which I employ in the construction of the wall are shown as made in two sections, K and L to make them collapsible. Each core in fact consists of two congruent individual cores which are rigidly connected 55 by a narrow neck portion and each of these two congruent parts has a lateral extension on the opposite outer portion. The cores are laid side by side as shown in Figs. 2 and 3 so that the lateral extensions meet. 60 By this arrangement the assembled, so to

say single members, form but one core which thus may be of any required length composed of a number of single members constituting each a double or twin core.

The section, K , is composed of a shell, k , shown as having a depression, k^1 , therein. To impart strength to the shell, k , ribs, as k^2 , may be fastened to the interior of the shell k , at the top and bottom thereof, and the space between the ribs, k^2 , and the shell, k , may be provided with a filling, k^3 , of wood or other desired material. This filling, k^3 , will give strength to the top and bottom of the section K . To this filling, k^3 , projections, as k^4 , are shown as fastened by k^5 .

Shoulders, as k^6 , are shown as provided in the interior of the shell, k , and slides or projections, k^7 , are shown as passing through the shell, k . These slides or projections, k^7 , are shown as provided with 85 slots, k^8 , in which screws, as k^9 , work.

Flaps k^{10} , of canvas or other desired material, are fastened to the side edges of the shell, k , and these flaps will preferably be provided with a facing, k^{11} , of metal.

l , designates the shell of the section, L . The interior of the shell, l , is shown as provided at the top and bottom thereof with ribs, l^1 , and the space between the ribs, l^1 , and the shell, l , may be provided with a filling, l^2 , of wood or other desired material, intended to impart additional strength to the top and bottom of the section, L . Projections, as l^3 , are shown as secured to the filling, l^2 , by the screws, l^4 , and slides or projections, l^5 , are shown as passing through the shell l , and these slides or projections, l^5 , are shown as provided with slots, l^6 , in which screws, as l^7 , work.

l^8 , designate arms in the interior of the shell, l . These arms, l^8 , are shown as having fastened thereto pieces, l^9 , of a width greater than the arms themselves. Staples, l^{10} , pass through holes in the arms, l^8 , and these staples are shown as secured to the ribs, l^1 . The staples, l^{10} , permit the arms, l^8 , to be turned. The arms, l^8 , are shown as passing through one end of the shell, l , and as terminating in handles, l^{11} . l^{12} , designates another arm in the interior of the shell, l . This arm, l^{12} , is shown as likewise having fastened to it a piece, l^{13} , of a width greater than the arm, l^{12} . Staples, l^{14} , pass through holes in the arm, l^{12} , and these staples, l^{14} , are shown as secured to the ribs, l^1 . The staples, l^{14} , permit the arm, l^{12} , to be turned. The arm, l^{12} , is shown as passing through one end of the shell, l , and as terminating in a handle, l^{15} .

The projections, k^4 and l^3 will be so disposed that when the sections, K and L , are placed in position one of the projections k^4 will be alongside one of the projections l^3 ; and the shoulders, k^6 , will be so disposed that when the arms, l^8 , are turned down said

90

105

110

115

120

125

130

arms or the pieces, l^9 , fastened thereto will enter the openings in the shoulders, k^6 .

The tops and bottoms of the section L fit over the tops and bottoms of the section K, and when the sections K and L are to be united they are brought together, and the flaps, k^{10} , are brought around the edges, l^{16} , of the section L. The flaps, k^{10} , and the edges, l^{16} , are then fastened together by 10 means of the screws, l^{17} , and nuts, l^{18} .

In order to prevent cement and other material from obtaining access to the interior of the core, flaps, as l^{19} , l^{20} and l^{21} , are shown as provided where the arms, l^8 and 15 l^{12} , extend out of the shell, l .

When it is desired to contract the core, the handle, l^{15} , is so turned as to cause the arm l^{12} to lie flat against the shell, l , and the arms, l^8 , are then turned down. As 20 the arms, l^8 , turn down they engage the shoulders, k^6 , and thereby the section K is carried inward, and the core contracted. When it is desired to expand the core the arms, l^8 , are turned up and the arm, l^{12} , then also 25 turned up. It will be readily understood that this arm l^{12} imparts rigidity to the sections K and L.

M designates a rod shown as fastened to the shell, l , by screws, m . The rod, M, is 30 shown as passing over a cross bar, N. The cross bar, N, is shown as provided with a slot, n , and the rod, M, and cross bar, N, are shown as fastened together by a bolt, m^1 , which passes through the slot, n . The cross 35 bar, N, is shown as provided with holes, n^1 through which bolts, n^2 , may be passed for the purpose of securing said cross bar, N, to the sides, I, I^1 .

Having determined on the thickness of 40 the wall to be erected, the sides, I and I^1 , are set in such position relatively to each other that the space between them will equal the thickness of the wall which if is desired to erect. This adjustment is effected by 45 suspending the bar, D, in proper position from the cross bar, C, the holes, c , permitting the bar, D, to be suspended in any desired position. After the bar D has been properly suspended, the projections, g , are 50 brought into engagement with the teeth of the racks, F, and the pieces, G, and racks F, forced downward until they reach a horizontal position. The side I, will thereby be held securely in position, the racks F forming 55 braces between the upright A and the bar D. Instead of using the pieces, G, I may place the projections g on the upright A, but I prefer to use the pieces, G, as I find that the racks, F, and projections, g , 60 may be more easily locked and unlocked from engagement with each other by the use of these pieces G. After the sides, I, I^1 , are securely locked in position, cores are suspended, preferably midway in the space between the sides, I and I^1 , and the cross bars,

N, from which the cores are suspended, are fastened to the sides, I, I^1 , by the bolts, n^2 . After the cores have been properly placed in position, the material, properly prepared, of which the wall is to be composed, is 70 poured into the space between the sides, I, I^1 , these sides, I, I^1 , forming a mold. The cores will cause the material of which the wall is to be composed to assume the form illustrated at O, Fig. 2, making a "hollow" 75 wall with ribs, o. The sides of the wall may, if desired, be bound together by steel rods.

When the material poured between the sides, I and I^1 , has hardened sufficiently, the 80 cross bars, N, are unfastened from the sides, I, I^1 , and the cores contracted by turning the handles, l^{11} , l^{15} , it being, of course, understood, that before the material is 85 poured into the space between the sides, I, I^1 , the cores have been in an expanded condition. When the cores have been contracted they may be withdrawn from between the sides, I, I^1 . I may then insert sides, as P, P^1 , on top of the sides, I, I^1 . These sides, 90 P, P^1 , are of the same general construction as the sides, I, I^1 , and form extensions of the sides, I, I^1 , the sides, P, P^1 , merely permitting a second section of the wall to be 95 cast before the section first cast has become sufficiently hardened to permit the withdrawal of the sides, I, I^1 .

The side, P, may, if preferred, be fastened to the bar, D, in any desired manner, and the side, P^1 , may likewise be fastened 100 to the bar H in any desired manner; although, in practice, I have found it unnecessary to so fasten the sides, P, P^1 .

When the sides, P, P^1 , have been properly placed in position, the cores, expanded, 105 are placed in proper position between them, and the cross bar, N, fastened to the sides, P, P^1 , by the bolts, n^2 . The slides or projections, k^7 and l^6 , serve to hold the lower ends of the cores in proper position and 110 against movement while the material is being poured into the space between the sides, P, P^1 .

While the cores may be so arranged for the casting of the second section of the wall 115 that the ribs, o, of the first section of the wall will be continued up in the second section, yet I prefer to so arrange the cores that in the casting of the second section the ribs, o, will be formed on the side of the wall opposite to that on which they were formed in the first section of the wall. The form which the wall will assume is illustrated in Figs. 2 and 5. By this form of construction the wall is materially strengthened because 120 the ribs formed on the second casting overlap the ribs on the first casting without interrupting the air space formed within the wall. In this form of wall the resulting air space is continuous and not interrupted 125 130

but in the second casting, etc., the air space is alternately formed by reversing the cores or by shifting same laterally. Furthermore both the inner and the outer wall are united by the ribs formed by reversing the cores in the second casting or by moving same sidewise while the space formed uninterrupted assumes the shape shown in Fig. 5 wherein the narrow spaces below the ribs of the second casting are plainly shown. Thus a peculiarly shaped double wall is formed joined by the overlapping cement ribs arranged alternately in the successive higher castings while a like peculiarly shaped continuous air space is formed. Tar paper or other material may, if desired, be used to cover the open spaces in the section of the wall first cast so as to prevent material poured between the sides, P, P¹, from falling into the open spaces in the section of the wall already cast.

After the material poured between the sides, P, P¹, has sufficiently hardened to permit the withdrawal of the sides, I, I¹, P, P¹, from their support of the sections of the wall already cast, the racks, F, are forced upward and unlocked, thereby releasing the tension between the upright A and the bar D. The sides, P, P¹, may then be withdrawn and the uprights, A, A¹, raised upward until the openings through which the pieces, J, are intended to be inserted are above the section of the wall last cast. When the pieces J are locked in position the uprights may be lowered so as to permit the pieces J to rest on the section of the wall last completed, and the racks F may again be brought down and locked to form braces between the upright A and the bar D. In this way the sides, I, I¹, will clamp the sides of the section of the wall last completed and the pieces J will aid in holding the frame work in place. It will, of course, be readily understood, that in casting the lowermost section of the wall the use of the pieces J is unnecessary, and the pieces J may be dispensed with entirely. Braces, might, for instance, be inserted under the uprights A, A¹. When the sides I, I¹ are in proper position the cores may again be placed in position and the operation of casting another section of the wall proceeded with.

By my improvement I am enabled to construct walls of great strength cheaply and expeditiously. The ribs not only strengthen the wall but afford support for the beams of the building. The large expense ordinarily incident to the scaffolding usually employed in the construction of "cement" and "concrete" walls is done away with, and the work may be carried on with unskilled labor, as there are no difficult adjustments of parts.

I produce walls absolutely "true" both

horizontally and vertically, and having a continuous air space, thereby rendering the wall damp proof and water proof. Furthermore these peculiarly shaped walls with the peculiarly shaped uninterrupted air space between retain a relatively uniform temperature within the house. Neither the heat of the summer nor the cold of the winter can penetrate these walls because the air mantle within the wall is an excellent insulator against heat and cold.

What I claim as my invention and desire to secure by Letters Patent is:

1. In an apparatus for casting double walls with interlocking tie-ribs, core-sections each having a body-portion and a reduced lateral extension for forming said tie-ribs said body-portion and extension having their outer surfaces within substantially the same plane, means comprising abutments for uniting said core-sections into multiples, and means for withdrawing said cores after casting, substantially as and for the purposes shown.

2. In an apparatus for casting double walls with interlocking tie-ribs, means for forming said tie-ribs comprising a multiple of cores consisting of vertical sided shells, and reduced lateral extensions connecting said shells, the outer surfaces of said extensions lying within the plane of the corresponding outer surfaces of the shells connected thereby, substantially as and for the purposes shown.

3. In a core for casting walls of buildings the combination of two vertically sided shells, a cover and a bottom to close the shells, all made of rigid material with guides fastened on the cover and bottom, and means for joining said shells comprising flaps fastened to the sides.

4. In a collapsible twin core for casting walls of buildings in combination, two congruent individual cores composed each of a vertically sided shell, a narrow neck on the inner central side portions rigidly connecting said shells, and a common bottom and cover to close said shells and neck, all made of rigid material, means for joining each shell comprising guides and flaps, means on the bottom of the cores for keeping same in position during use, adjustable means for suspending the cores between the mold walls, and means for expanding and collapsing same comprising shoulders on the inner side of one shell and arms on the opposite inner side of the same.

5. A multiple continuous core for casting walls of buildings between mold walls consisting of a number of single members arranged side by side and adapted to be adjustably locked between said mold walls, each single member comprising two congruent individual cores composed each of a vertically sided shell, a narrow neck on the inner

80

105

110

115

120

125

130

- central side portions rigidly connecting said shells, and a common bottom and cover to close said shells and neck, all made of rigid material, means for joining each shell comprising guides and flaps, means on the bottom of the cores for keeping same in position during use, adjustable means for suspending the cores between the mold walls, and means for expanding and collapsing same comprising shoulders on the inner side of one shell and arms on the opposite inner side of the same extending through the cover and bent to form a handle for effecting the expansion and collapse of the core.
6. The combination of uprights, a bar fastened to said uprights, another bar depending from the first mentioned bar, means for locking said secondly mentioned bar against one of said uprights, and mold walls carried by said last mentioned bar.
7. The combination of uprights, a bar fastened to said uprights, another bar depending from the first mentioned bar, means for adjusting said secondly mentioned bar on said first mentioned bar, means for locking said secondly mentioned bar against one of said uprights, and mold walls carried by said last mentioned bar.
8. The combination of uprights, a bar fastened to said uprights, another bar depending from the first mentioned bar, means for adjusting said secondly mentioned bar on said first mentioned bar, means for locking said secondly mentioned bar against one of said uprights, a mold and means for attaching said secondly mentioned bar to one of the sides of said mold and a mold side adapted to be secured to said attaching means.
9. The combination of uprights, a bar fastened to said uprights, another bar depending from the first mentioned bar, means for adjusting said secondly mentioned bar on said first mentioned bar, means for locking said secondly mentioned bar against one of said uprights, a mold, means for attaching said secondly mentioned bar to one of the sides of a mold, another bar fastened to the other of said uprights, and means for attaching said last mentioned bar to one of the sides of the mold.
10. The combination of uprights, a bar fastened to said uprights, another bar depending from the first mentioned bar, means for locking said secondly mentioned bar against one of the uprights, a mold the sides of which are held between the secondly mentioned bar and one of the uprights, and cores suspended from the sides of the mold.
11. The combination of uprights, a bar fastened to said uprights, another bar depending from the first mentioned bar, means for locking said secondly mentioned bar against one of the uprights, a mold the sides of which are held between the secondly mentioned bar and one of the uprights, and collapsible cores suspended from the sides of the mold.
12. The combination of uprights, a bar fastened to said uprights, another bar depending from the first mentioned bar, means for adjusting said secondly mentioned bar on said first mentioned bar, means for locking said secondly mentioned bar against one of the uprights, a mold the sides of which are held between the secondly mentioned bar and one of the uprights, and brackets detachably secured to the mold.
13. The combination of uprights, a bar fastened to said uprights, another bar depending from the first mentioned bar, means for adjusting said secondly mentioned bar on said first mentioned bar, means for locking said secondly mentioned bar against one of the uprights, a mold the sides of which are held between the secondly mentioned bar and one of the uprights, brackets detachably secured to the mold, and collapsible cores suspended from the sides of the mold.
